AMPULE CLEANSING MACHINE

Frank Cozzoli, Plainfield, N. J.

Application September 13, 1941, Serial No. 410,727

3 Claims. (Cl. 134—72)

This invention relates to washing machinery, and more particularly to machinery used in cleansing, sterilizing and drying containers.

A particular object of the invention is to provide a machine adapted to the sanitary handling of containers through a plurality of steps, cleansing, and automatically delivering the sterile containers without being touched by human hands.

A further object is to provide a machine of the character described, which will be adapted to handle delicate containers, such as ampules, and to move such containers through various stages of sterilization and to submit them to successive cleansing operations so that each ampule when delivered will have been subjected to a specific treatment for a predetermined period of time. In washing or cleansing ampules it is necessary to subject them to successive treatments with various materials. This treatment may vary depending upon the use to which the ampules are to be put, but, as an example, may consist of a strong cleansing solution in the first step, a rinsing solution in the second, steam in the third, and hot air for drying purposes in the fourth stage. I have shown a machine adapted to pass through six successive stages, but it will be appreciated that any number of stages may be used.

A still further object is to provide means whereby the washing stages are kept separate from one another so that the ampules are subjected only to the predetermined treatment which is to be used at each stage. Means are therefore provided to regulate the amount of solution or liquid which is to be used as well as the amount of air which may be used at each stage to dry out the solution of liquid before the ampules are moved to the next stage.

In the accompanying drawings—

Fig. 1 is a side elevation partly broken away to show the operation of my machine;

Fig. 2 is a top plan view of a portion thereof;

Fig. 3 is a cross-sectional view taken on the line 3—3 of Fig. 1;

Fig. 4 is a plan view of the trough and nozzle sections;

Fig. 5 is a cross-sectional view taken on the line 5—5 of Fig. 1;

Fig. 6 is a cross-sectional view taken on the line 6—6 of Fig. 5;

Fig. 7 is a cross-sectional detail view of the nozzle unit;

Fig. 8 is a plan view of the unloading mechanism;

Fig. 9 is a sectional view showing the operation of the trough;

Fig. 10 is a view similar to Fig. 5 showing the operation of the fluid control means;

Fig. 11 is a side elevation of the cam shaft used to control the switches operating the valves which determine the amount of fluid or air used;

Fig. 12 is a cross-sectional view on the line 12—12 of Fig. 11;

Fig. 13 is a cross-sectional view on the line 13—13 of Fig. 1.

My machine includes a frame 10 of any suitable type having a table 11 and a shelf 12. Mounted on the shelf 12 is a motor 13 which by means of a belt or chain 14 and a gear box 15 rotates the shaft 16 on which is mounted a sprocket 17 engaging the chain 18. On the other end of the shaft 16 is mounted an arm 19 bearing a cam roller 20. The chain 18 engages a sprocket 25 mounted on the shaft 26. Also mounted on the shaft 26 is a double arm 27 carrying a cam roller 28.

Pivoted at 30 to an extension of the table 11 is a lever arm 31. At the opposite end of the arm 31 is a pawl 32. Mounted on the shafts 33 and 34 are two pairs of sprockets 35 and 36. Also mounted on the shaft 34 is a ratchet 37, and it will be seen that as the shaft 26 rotates, due to the action of the chain 18 on the sprocket 25, the lever arm 31 will be contacted by the roller 28 which will cause it to rise and fall. This will cause the pawl 32 to engage the ratchet 37 and intermittently rotate the shaft 34 and the sprocket 36.

Mounted for rotation on the sprockets 35 and 36 are a series of units 40 pivoted at their ends 41 by pins 42 to form an endless linked belt. The nature of these units may be best seen in Fig. 7. Each unit consists of a tray or trough 43 through the center of which are a series of tube members 44 bearing washers or bumpers 45 and positioned by means of the threaded members 46 and 47. The member 47 tapers at its lower end to form a nipple 48 which is adapted to be engaged by the socket 50.

The socket 50 is provided with a soft rubber washer 51 and is mounted on the tube 55 in the bar 54. The tube 55 is slidably mounted in the bar 54 and a spring 52 exerts upward pressure against the socket 50. A lock washer 56 limits the upward movement of the tube. The lower end of the tube 55 forms a nipple 57. The bars 54 are mounted on a carriage 58 which is provided with tubular end members or sleeves 60 slidably mounted on the supports 61. Mounted

on the lower end of the tubular member 60 are rollers 62.

The shaft 26 is provided with cams 65 adapted to engage the rollers 62 on the carriage 58. It will be seen that upon each rotation of the shaft 26 the carriage 58 will be raised and the sockets 50 brought into pressure engagement with the nipples 48. The cam 65 and the cam roller 28 are so positioned upon the shaft 26 that the roller cam 28 will not be in engagement with the lever arm 31 while the high portion of the cam 65 is in engagement with the rollers 62 so that the sockets 50 will be out of engagement with the nipple 48 when the arm 31 and the pawl 32 move the ratchet 37 and sprockets 35 and 36.

As will be apparent from Fig. 1, the rotation is in a clockwise direction, and at the discharge end of the machine a shield 10 is provided to maintain the ampules A on the tubes 44 until they reach the end 71 of the shield 10.

In the framework 72 is a slot 73. A plunger bar 74 operates in the slot 73 in the following manner: The fork 75 is pivoted at 76 to either end of the bar 74 and merges into the arm 77 pivoted at 78. As the shaft 16 rotates in a counter-clockwise direction, the roller arm 20 disengages the arm 77 and allows it to drop to the dotted position shown in Fig. 1. This allows the bar 74 to drop in the slot 73 and thus removes the ampule A from the tube 44 to a level with the tray on the shelf 79.

Mounted on the support 80 is a pusher 81 having a plurality of fingers 82 spaced from each other to coincide with the number of tubes 44 in each of the units 40.

Pivoted at 83 to the shelf 12 is an arm 84 which in turn is linked by the members 85 to the rear of the pusher 81. A spring 87 engages the arm 84 to normally hold the pusher in a rearward position and to clear the slot 73. As the cam roller 82 rotates it engages the arm 84 and forces it against the spring 87 so that the pusher will move the ampules from the top of the bar 74 onto the tray. As the roller moves along the arm 84 into the slot 86 pressure on the arm 84 is relieved and the spring 87 will cause the arm 84 to snap back and to move the pusher 81 out of the path of the bar 74 as the roller engages the arm 77 to move the bar 74 upwardly to receive additional ampules.

Mounted above the table 10 is a frame 90 carrying a motor 91 which operates the belt 92. The belt 92 rotates a series of pulleys 93. The pulleys 93 are positioned above each ampule and engage a washer 94 by means of a shaft 95. The washers 94 are adapted to engage the top of each ampule as it is forced upwardly by the pressure of the cleansing fluid to cause it to spin during the cleansing operation, thus insuring a complete cleansing.

Each unit 40 is provided with a roller 49 on the pin 42 which engages a track 102 so that when the bar 54 is raised upwardly the unit 40 will be steadied and maintained in position. The rollers 49 are also engaged by the sprockets 35 and 36 to move the linked belt.

As previously pointed out, each unit 40 has a series of tubes mounted therein. In my machine I have shown four tubes but any convenient number may be applied. Each unit 40 is supplied with a trough 43 to collect cleansing fluid or other material as it drains from the ampules.

In the machine as described six stages are provided, that is, each ampule moves through six intermittent movements and may receive six

separate and distinct treatments, four of which would normally be liquid or steam, and the last two drying air, and there may therefore be six different types of fluid to be collected from the trough 43. I accordingly provide means for separating and collecting said fluid, as in some instances the fluid may be used again.

In Fig. 3 it will be seen that on either side of the machine are provided troughs 96 which are sub-divided so as to lead to separate tubes 97 for drainage purposes. A plan view of these troughs is shown in Fig. 9, and it will be seen that each trough 43 discharges into a separate drainage trough so that the fluids used in each operation are kept separate and may be re-used. The discharge issuing from these troughs flows into the several channels 98' of troughs 96 through a series of sluice-ways 43' of staggered lengths each sluice-way being directed into a separate channel.

Leading to each of the nipples 57 is a hose 100 which connects with a manifold 101. Each of the manifolds 101 is provided with valves 103 at one end and valves 104 at the other end. Leading from the valve 103 is a pipe 105 which may lead to an air or steam source, and from the valve 104 a pipe 106 may lead to a liquid source. The valves 103 and 104 are of the solenoid variety which will open when the circuit controlling the solenoid is closed, and close under spring pressure when the circuit is broken.

Mounted on the frame 10 are brackets 111 bearing the cam shaft 112 which is rotated by the chain 113 and the sprockets 114 and 114' from the shaft 26. The shaft 112 carries six cam members 115 which are identical in construction and one cam member 116 which is slightly different in construction. The cam members 115 may be one continuous cam or six separate ones as shown. Each of the cam members 115 is adapted to operate a switch 120, there being six switches, one for each stage of the operation. The cam member 116 is adapted to operate a switch identical in all respects with the switch 120 but controlling the flow of air through all of the stages.

The switch 120 is mounted on a bracket 121 and is adapted to pivot thereon at 122. It consists of two contact members—one stationary member 123, and one spring member 124. The spring member 124 has an extended frame 125 adapted to engage the cam. An angle iron 126 is fixed to the base 10 and bears a screw 127 engaging the rear of the switch 120. A light spring 128 tends to keep the switch member upwardly against the screw 127.

It will be appreciated that the switches operated by the cams 115 each operate one of the valves 104 controlling the flow of liquid while the switch operated by the cam 116 controls all of the valves 103 controlling the flow of air or dry steam. The amount of fluid supplied in each stage may be controlled by the adjustment of the screw 121 on the switch controlling that stage. In other words, the screw 121 may be adjusted so that the flexible end 125 is engaged by the cam for a longer or shorter period of time. By screwing the screw 121 downwardly the flexible member 125 will engage the cam sooner than when the screw 121 is screwed outwardly or upwardly. The amount of air delivered in each stage may also be controlled by the adjustment of the switch 120 controlling the valves 103. It will be seen that different amounts of fluid may be delivered in each of the different stages by causing the

valve 104 controlling that stage to open sooner. All of the valves 104 will of course close simultaneously at which point the cam 116 will cause all of the valves 103 to open for a predetermined time.

In operation the ampules may be placed upon the tubes 44 from the table 11 either by hand or by means of an automatic feeding mechanism (not shown). As the series of units 40 are intermittently moved forward, the ampules will come under the washers 94. At that stage the upward movement of the carriage 58 will cause the sockets 50 to engage the nipple 48 and the valves 104 will be opened by their respective switches 120 in accordance with the predetermined pattern. The ampules will then be subjected to a cleansing fluid, either liquid or gaseous, and will be forced against the washers 94 and thus rotated. As the high point of the cam 115 passes over the spring member 124, the valves 104 will close and at the same time the valves 103 will be opened by the switch engaging the cam 116 allowing a blast of air or drying gas to be delivered to the tubes 44 to blow them and the ampules free of liquid. The carriage 58 will then drop and the units will be moved into the second phase where the operation will be repeated with the desired cleansing fluid.

As shown in the drawings, each ampule will be moved through six stages and be subjected to six treatments with a drying operation after each treatment. The ampules will then move against the shield 70 and be deposited on the tray.

As has been previously stated, I have shown units adapted to carry four ampules, but it will be appreciated that any number of ampules may be carried by a single unit and the ampules may be subjected to any number of intermittent treatments without departing from the invention herein disclosed.

I claim:

1. In a conveyor type washing machine, a continuous linked belt, each of the links of said belt comprising an elongated run-off trough for discharge fluids, said trough being transversely dis-

posed to the direction of movement of the belt and open at both ends, a series of sluice-ways situated at each end of said run-off troughs and communicating therewith, said sluice-ways being of staggered lengths, a receiving trough communicating with each said series of sluice-ways, said receiving trough being longitudinally divided into separate channels, each channel communicating with a separate sluice-way, and a lead-off conduit communicating with each said channel at the discharge point of said channel.

5 2. In a conveyor type washing machine, a series of washing units, each of said units constituting a trough, a plurality of washing tubes extending through said trough, a nipple on the underside of each trough communicating with each of said washing tubes, means for moving said troughs and thereby said tubes intermittently, means for supplying different cleaning agents through said nipples to said tubes in the intervals between their intermittent movements, a second trough divided into separate channels, and a series of sluice-ways of staggered lengths communicating respectively with said separate channels and receiving the flow of the first mentioned troughs and delivering said flow to the different channels of the second trough for separate collection thereof.

10 3. In a conveyor type washing machine, a series of washing units, each of said units constituting a trough, a plurality of washing tubes extending through said trough, means for moving said troughs and thereby said tubes intermittently, means for supplying different cleaning agents to said tubes in the intervals between their intermittent movements, a second trough divided into separate channels, and a series of sluice-ways of staggered lengths communicating respectively with said separate channels and receiving the flow of the first mentioned troughs and delivering said flow to the different channels of the second trough for separate collection thereof.

FRANK COZZOLL.
